UNITED STATES PATENT OFFICE.

AUGIE L. HANSEN, OF CHICAGO, ILLINOIS, ASSIGNOR TO HANSEN MANUFACTURING COMPANY, OF THE COUNTY OF COOK, OF ILLINOIS, A CORPORATION OF ILLINOIS.

DESIGN FOR A DISPLAY STAND FOR PACKAGED GOODS.

Application filed June 4, 1924. Serial No. 9,798. Term of patent 7 years.

To all whom it may concern:

Be it known that I, AUGIE L. HANSEN, a citizen of the United States, and resident of Chicago, in the county of Cook, State of Illinois, have invented a new, original, and ornamental Design for Display Stand for Packaged Goods, of which the following is a specification, reference being had to the accompanying drawing, forming a part thereof, in which—

I claim:

The ornamental design for a display stand for packaged goods as shown.

Dated at Chicago, Illinois, this 28 day of May, A. D. 1924.

AUGIE L. HANSEN.
